UNITED STATES PATENT OFFICE.

FRANZ J. WOOD, OF DES MOINES, IOWA.

SPEED-GOVERNOR.

1,031,670.

Specification of Letters Patent.

Patented July 2, 1912.

Application filed September 10, 1906. Serial No. 333,944.

To all whom it may concern:

Be it known that I, FRANZ J. WOOD, a citizen of the United States, residing at Des Moines, in the county of Polk and State 5 of Iowa, have invented a certain new and useful Speed-Governor, of which the following is a specification.

My object is to provide a speed governor of simple, durable and inexpensive construction by which power may be transmitted from a traveling chain to a rotatable shaft or vice versa, and the speed of travel of one be automatically regulated by the speed of travel of the other, and further to provide 15 means whereby a positive driving connection may be made between the chain and shaft.

My invention consists in certain details in the construction, arrangement and combination of the various parts of the device, whereby the objects contemplated are attained, as hereinafter more fully set forth, pointed out in my claims and illustrated in the accompanying drawings, in which—

25 Figure 1 shows a side elevation of a device embodying my invention. Fig. 2 shows a face view of one of the disks to be engaged by the chain. Fig. 3 shows a face view of the weighted levers and the frame 30 for supporting them. Fig. 4 shows the opposite side of the disk illustrated in Fig. 2 with the sprocket wheel in position thereto and a sprocket chain passing around the sprocket wheel and out of contact therewith. 35 Fig. 5 shows a vertical, central, sectional view of the governing device embodying my invention, the upper sprocket wheel and connected parts being omitted. Fig. 6 shows an enlarged detail, sectional view on 40 the line 6—6 of Fig. 5 illustrating the rollers and tapered arm in their relative positions, and Fig. 7 shows an enlarged, central, sectional view of a modified form of governor in which both of the chain engaging disks 45 are provided with governing devices for moving the disks in unison toward and from each other.

Referring to the accompanying drawings, I have used the reference numeral 10 to indicate a rotatable shaft. A stationary disk 11 is fixed to this shaft by the set screw 12 and has one face beveled from its axis to its periphery away from the other disk.

Fixed to the shaft 10 adjacent to the center of the disk 11 is a small sprocket rim 13 55 held to the shaft by the pin 14. Adjacent to the said sprocket rim is a disk 15 slidingly and non-rotatably mounted on the shaft and having its face, that is adjacent to the sprocket rim, beveled from its center 60 toward its periphery, the adjacent faces of the disks 11 and 15 being spaced apart and the space between them being narrowest at the center. Fixed to the shaft 10 by means of the pin 16 is a frame 17 adjacent to the 65 outer face of the disk 13. This frame is connected with the disk 13 by means of a number of guide pins 18 extending through the disk and frame and so arranged that the disk may freely move toward or from the 70 frame, but may not rotate relative thereto.

I have provided means for yieldingly holding the disk toward the frame as follows: The numeral 19 indicates bolts fixed to the disk and slidingly mounted in the 75 frame. On said bolts are the extensible coil springs 20, one end of each spring bearing against the frame and the other against an adjustable nut on the bolt 19, whereby the tension of the spring may be regulated. 80 The frame 17 also supports three weighted levers, each of which comprises a hub 22 mounted upon one of the pins 18 and formed with a wedge-shaped extension 23 and with an arm 24 on which a weight 25 is 85 adjustably secured by the set screw 26. Adjacent to the wedge-shaped extensions 23 is an anti-friction roller 27 mounted in the frame 17 and a similar roller 28 mounted in the disk 15. These parts are so constructed and arranged that when the shaft 10 is at rest, the springs 20 will force the disk 15 and frame 17 together, thus causing the rollers 27 and 28 to engage the wedge-shaped extension 23 and thereby hold 90 the weighted levers 24 to their inner limit of movement. Then assuming that the shaft 10 is rotated, the weighted levers will move outwardly by centrifugal force and cause the disk 15 to move away from the frame 17 95 100 on account of the wedge-shaped extension 23 acting upon the roller 28 to force the disk 15 away from the frame. Rotatably mounted at some distance from the shaft 10 is a second shaft 29 upon which is fixed 105 a gear-wheel 30. On the same shaft is

mounted a lever 31 provided with a spring actuated pawl 32 to engage a stationary rack 33 by which the lever may be supported in various positions. Rotatably mounted on the lever 31 is a shaft 34 having fixed to it a gear-wheel 35 meshed with the gear-wheel 30 and also a sprocket wheel 36. A sprocket chain 37 is passed around the sprocket wheel 36 and also around the sprocket wheel 13 and between the disks 11 and 15. The links of the sprocket chain are provided with lateral extensions 38 at their sides to engage the faces of the disks 11 and 15 when said disks are moved toward each other, so that they may engage the said extension.

In practical use and assuming that motion is to be transmitted from the shaft 10 to shaft 34, it is obvious that as the shaft 10 starts to move, the shaft 34 will be positively driven by the sprocket wheels 13 and 36 and the chain 37. This action is just as positive as though the disks 11 and 15 were omitted. Assuming further that the speed of rotation of the shaft 10 is increased materially, then the centrifugal action of the weighted levers will move the disk 15 toward the disk 11, thus wedging the chain between the disks and forcing the chain out of engagement with the sprocket wheel 13. The portion of the chain that travels around the shaft 10 will move outwardly from the shaft as the speed of rotation of the shaft increases and will move inwardly toward the shaft as the speed decreases until the links thereof again engage the sprocket wheel 13. When the links of the chain engage the disks 11 and 15 at the maximum distance from their centers, then the shaft 34 will be driven at its maximum speed relative to the shaft 10 and when the sprocket chain engages the sprocket wheel 13, the shaft 34 will be driven at its minimum speed relative to the shaft 10. This action is entirely automatic, if there is sufficient slack in the chain to permit the part thereof that passes around the shaft 10 to travel toward and from the center of the shaft in this manner.

Assuming that it is desirable to drive the shaft 34 at its minimum speed when the shaft 10 is rotating, at its maximum speed, then the lever 31 is manipulated to take up the slack in the chain and thus positively force the links of the chain to wedge themselves between the disks until the links of the chain engage the sprocket wheel 13. This will prevent the automatic action of the movable disk and produce a positive drive of the sprocket chain.

In the modified form of my invention, illustrated in Fig. 7, I have made both of the chain engaging disks alike and provided each with independent governing devices 65 for moving the disks toward and from each

other in unison. In this form of invention, I have used the reference symbol 11^a to indicate a movable chain engaging disk that is substituted for the stationary disks 11, as shown in Fig. 5. The governing devices controlling this disk 11^a are identical with the ones just before described and hence a detail description of said governing device is unnecessary. The advantage to be gained by having both disks movable relative to each other and relative to the sprocket wheel 13 is that as the chain is moved by the friction disks to and from position in engagement with the sprocket wheel, the sprocket chain will at all times be in position accurately centered over the sprocket wheel, while with the form of invention shown in Fig. 5 and assuming that the chain is at its outer limit of movement away from the sprocket wheel, then it would not be centered directly over the sprocket wheel, but will be at the side thereof toward the stationary disk 11. In some instances this lateral movement of the sprocket chain is objectionable but by having both disks moved at the same time and to the same degree, then the sprocket chain at all times remains accurately centered over the sprocket wheel.

It is obvious that if the sprocket wheel 36 is firmly fixed at its limit of movement away from the sprocket wheel 13, then the sprocket chain 37 will be held firmly in engagement with the sprocket wheel 13 regardless of the action of the movable disks 100 toward and from each other. Furthermore, if the sprocket wheel 36 is set in any other position of its adjustment, then the movement of the chain 37 away from the sprocket wheel 13 will be limited regardless of the amount of pressure applied by the centrifugal weights tending to force the disks toward each other, hence, the means for adjusting the sprocket wheel 36 is in fact a means for limiting the movement of the sprocket chain away from the sprocket wheel. If however, the disk 36 is set in such position that there is sufficient slack in the chain to permit the chain to move from the sprocket wheel 13 toward the peripheries 115 of the adjacent disks, and back, then the action of the disks will be automatic and will be controlled by the speed of rotation of the disks as before explained.

Having thus described my invention, what I claim and desire to secure by Letters Patent of the United States, therefor is—

1. The combination of a sprocket wheel, a sprocket chain passed around it and chain engaging devices arranged to rotate with the sprocket wheel and capable of forcing the chain outwardly from engagement with the sprocket wheel while maintaining driving engagement with the chain.

2. The combination of a sprocket wheel,

5 a sprocket chain passed around it and chain
engaging devices arranged to rotate with
the sprocket wheel and capable of automatically
forcing the chain outwardly from
engagement with the sprocket wheel while
5 maintaining driving engagement with the
chain.

10 3. The combination of a sprocket wheel,
a sprocket chain passed around it and cen-
trifugally actuated chain engaging devices
arranged to rotate with the sprocket wheel
and capable of forcing the chain outwardly
from engagement with the sprocket wheel
while maintaining driving engagement with
15 the chain.

20 4. The combination of a sprocket wheel,
a sprocket chain passed around it, chain en-
gaging devices arranged to rotate with the
sprocket wheel and capable of forcing the
chain outwardly from engagement with the
sprocket wheel while maintaining driving
engagement with the chain, and a yielding
pressure device to act in opposition to the
means for forcing the chain outwardly from
25 the sprocket wheel.

30 5. The combination of a sprocket wheel,
a sprocket chain passed around it, chain en-
gaging devices arranged to rotate with the
sprocket wheel and capable of automatically
forcing the chain outwardly from engage-
ment with the sprocket wheel while main-
taining driving engagement with the chain
and a yielding pressure device to act in op-
position to the means for forcing the chain
35 outwardly from the sprocket wheel.

40 6. The combination of a sprocket wheel,
a sprocket chain passed around it, centrifu-
gally actuated chain engaging devices ar-
ranged to rotate with the sprocket wheel
and capable of forcing the chain outwardly
from engagement with the sprocket wheel
45 while maintaining driving engagement with
the chain and a yielding pressure device to
act in opposition to the means for forcing
the chain outwardly from the sprocket
wheel.

50 7. The combination of a sprocket wheel,
a sprocket chain passed around it, chain en-
gaging devices arranged to rotate with the
sprocket wheel and capable of forcing the
chain outwardly from engagement with the
sprocket wheel while maintaining driving
engagement with the chain and means for
positively forcing the sprocket chain into
55 engagement with the sprocket wheel.

60 8. The combination of a sprocket wheel, a
sprocket chain passed around it, chain engag-
ing devices arranged to rotate with the
sprocket wheel and capable of automatically
forcing the chain outwardly from engage-
ment with the sprocket wheel while main-
taining driving engagement with the chain
and means for positively forcing the
sprocket chain into engagement with the
65 sprocket wheel.

9. The combination of a sprocket wheel,
a sprocket chain passed around it, centrifu-
gally actuated chain engaging devices ar-
ranged to rotate with the sprocket wheel
and capable of forcing the chain outwardly
from engagement with the sprocket wheel
70 while maintaining driving engagement with
the chain and means for positively forcing
the sprocket chain into engagement with the
sprocket wheel.

75 10. The combination of a sprocket wheel,
a sprocket chain passed around it, chain en-
gaging devices arranged to rotate with the
sprocket wheel and capable of forcing the
chain outwardly from engagement with the
80 sprocket wheel while maintaining driving
engagement with the chain, a yielding pres-
sure device to act in opposition to the means
for forcing the chain outwardly from the
sprocket wheel and means for positively
85 forcing the sprocket chain into engagement
with the sprocket wheel.

90 11. The combination of a sprocket wheel,
a sprocket chain passed around it, chain en-
gaging devices arranged to rotate with the
sprocket wheel and capable of automatically
forcing the chain outwardly from en-
gagement with the sprocket wheel while
95 maintaining driving engagement with the
chain, a yielding pressure device to act in
opposition to the means for forcing the
chain outwardly from the sprocket wheel
and means for positively forcing the
sprocket chain into engagement with the
100 sprocket wheel.

105 12. The combination of a sprocket wheel,
a sprocket chain passed around it, centrifu-
gally actuated chain engaging devices ar-
ranged to rotate with the sprocket wheel
and capable of forcing the chain outwardly
from engagement with the sprocket wheel
110 while maintaining driving engagement with
the chain, a yielding pressure device to act
in opposition to the means for forcing the
chain outwardly from the sprocket wheel
and means for positively forcing the
sprocket chain into engagement with the
115 sprocket wheel.

120 13. The combination of a sprocket wheel,
a sprocket chain passed around it, chain en-
gaging devices arranged to rotate with the
sprocket wheel and capable of forcing the
chain outwardly from engagement with the
sprocket wheel while maintaining driv-
ing engagement with the chain and manu-
ally operated means for positively forcing
the sprocket chain into engagement with
the sprocket wheel.

125 14. The combination of a sprocket wheel,
a sprocket chain passed around it, chain en-
gaging devices arranged to rotate with the
sprocket wheel and capable of automatically
forcing the chain outwardly from en-
gagement with the sprocket wheel while
130 maintaining driving engagement with the

chain and manually operated means for positively forcing the sprocket chain into engagement with the sprocket wheel.

15. The combination of a sprocket wheel, 5 a sprocket chain passed around it, centrifugally actuated chain engaging devices arranged to rotate with the sprocket wheel and capable of forcing the chain outwardly from engagement with the sprocket wheel 10 while maintaining driving engagement with the chain and manually operated means for positively forcing the sprocket chain into engagement with the sprocket wheel.

16. The combination of a sprocket wheel, 15 a sprocket chain passed around it, chain engaging devices arranged to rotate with the sprocket wheel and capable of forcing the chain outwardly from engagement with the sprocket wheel while maintaining driving 20 engagement with the chain, a yielding pressure device to act in opposition to the means for forcing the chain outwardly from the sprocket wheel and manually operated means for positively forcing the sprocket 25 chain into engagement with the sprocket wheel.

17. The combination of a sprocket wheel, a sprocket chain passed around it, chain engaging devices arranged to rotate with the 30 sprocket wheel and capable of automatically forcing the chain outwardly from engagement with the sprocket wheel while maintaining driving engagement with the chain, a yielding pressure device to act in 35 opposition to the means for forcing the chain outwardly from the sprocket wheel and manually operated means for positively forcing the sprocket chain into engagement with the sprocket wheel.

40 18. The combination of a sprocket wheel, a sprocket chain passed around it, centrifugally actuated chain engaging devices arranged to rotate with the sprocket wheel and capable of forcing the chain outwardly from 45 engagement with the sprocket wheel while maintaining driving engagement with the chain, a yielding pressure device to act in opposition to the means for forcing the chain outwardly from the sprocket wheel 50 and manually operated means for positively forcing the sprocket chain into engagement with the sprocket wheel.

19. The combination of a sprocket wheel, a sprocket chain passed around it, chain 55 engaging devices arranged to rotate with the sprocket wheel and capable of forcing the chain outwardly from engagement with the sprocket wheel while maintaining driving engagement with the chain and means for 60 limiting the movement of the sprocket chain away from the sprocket wheel.

20. The combination of a sprocket wheel, a sprocket chain passed around it, chain 65 engaging devices arranged to rotate with the sprocket wheel and capable of automatically

forcing the chain outwardly from engagement with the sprocket wheel while maintaining driving engagement with the chain and means for limiting the movement of the sprocket chain away from the sprocket 70 wheel.

21. The combination of a sprocket wheel, a sprocket chain passed around it, centrifugally actuated chain engaging devices arranged to rotate with the sprocket wheel 75 and capable of forcing the chain outwardly from engagement with the sprocket wheel while maintaining driving engagement with the chain and means for limiting the movement of the sprocket chain away from the 80 sprocket wheel.

22. The combination of a sprocket wheel, a sprocket chain passed around it, chain engaging devices arranged to rotate with the sprocket wheel and capable of forcing the 85 chain outwardly from engagement with the sprocket wheel while maintaining driving engagement with the chain, a yielding pressure device to act in opposition to the means for forcing the chain outwardly from the sprocket wheel and means for limiting the 90 movement of the sprocket chain away from the sprocket wheel.

23. The combination of a sprocket wheel, a sprocket chain passed around it, chain 95 engaging devices arranged to rotate with the sprocket wheel and capable of automatically forcing the chain outwardly from engagement with the sprocket wheel while maintaining driving engagement with the chain, a yielding pressure device to act in opposition to the means for forcing the chain outwardly from the sprocket wheel and means for limiting the movement of the sprocket 100 chain away from the sprocket wheel.

24. The combination of a sprocket wheel, a sprocket chain passed around it, centrifugally actuated chain engaging devices arranged to rotate with the sprocket wheel and capable of forcing the chain outwardly from 110 engagement with the sprocket wheel while maintaining driving engagement with the chain, a yielding pressure device to act in opposition to the means for forcing the chain outwardly from the sprocket wheel and means for limiting the movement of the sprocket 115 chain away from the sprocket wheel.

25. The combination of a sprocket wheel, a sprocket chain passed around it, chain 120 engaging devices arranged to rotate with the sprocket wheel and capable of forcing the chain outwardly from engagement with the sprocket wheel while maintaining driving engagement with the chain and adjustable means for limiting the movement of the sprocket 125 chain away from the sprocket wheel.

26. The combination of a sprocket wheel, a sprocket chain passed around it, chain 130

gaging devices arranged to rotate with the sprocket wheel and capable of automatically forcing the chain outwardly from engagement with the sprocket wheel while maintaining driving engagement with the chain and adjustable means for limiting the movement of the sprocket chain away from the sprocket wheel.

27. The combination of a sprocket wheel, a sprocket chain passed around it, centrifugally actuated chain engaging devices arranged to rotate with the sprocket wheel and capable of forcing the chain outwardly from engagement with the sprocket wheel while maintaining driving engagement with the chain and adjustable means for limiting the movement of the sprocket chain away from the sprocket wheel.

28. The combination of a sprocket wheel, a sprocket chain passed around it, chain engaging devices arranged to rotate with the sprocket wheel and capable of forcing the chain outwardly from engagement with the sprocket wheel while maintaining driving engagement with the chain, a yielding pressure device to act in opposition to the means for limiting the movement of the sprocket chain away from the sprocket wheel.

29. The combination of a sprocket wheel, a sprocket chain passed around it, chain engaging devices arranged to rotate with the sprocket wheel and capable of automatically forcing the chain outwardly from engagement with the chain, a yielding pressure device to act in opposition to the means for limiting the movement of the sprocket chain away from the sprocket wheel.

30. The combination of a sprocket wheel, a sprocket chain passed around it, centrifugally actuated chain engaging devices arranged to rotate with the sprocket wheel and capable of forcing the chain outwardly from engagement with the sprocket wheel while maintaining driving engagement with the chain, a yielding pressure device to act in opposition to the means for forcing the chain outwardly from the sprocket wheel and adjustable means for limiting the movement of the sprocket chain away from the sprocket wheel.

31. The combination of a sprocket wheel, a sprocket chain, two disks arranged on opposite sides of the sprocket wheel to rotate in unison with it, the adjacent faces of said disks beveled from their centers outwardly and away from each other and means for moving one toward the other.

32. The combination of a sprocket wheel, a sprocket chain, two disks arranged on opposite sides of the sprocket wheel to rotate in unison with it, the adjacent faces

of said disks beveled from their centers outwardly and away from each other and automatic means for moving one toward the other.

33. The combination of a sprocket wheel, a sprocket chain, two disks arranged on opposite sides of the sprocket wheel to rotate in unison with it, the adjacent faces of said disks beveled from their centers outwardly and away from each other and centrifugally actuated means for moving one toward the other.

34. The combination of a sprocket wheel, a sprocket chain, two disks arranged on opposite sides of the sprocket wheel to rotate in unison with it, the adjacent faces of said disks beveled from their centers outwardly and away from each other, means for moving one toward the other and a yielding pressure device normally tending to separate the disks.

35. The combination of a sprocket wheel, a sprocket chain, two disks arranged on opposite sides of the sprocket wheel to rotate in unison with it, the adjacent faces of said disks beveled from their centers outwardly and away from each other, automatic means for moving one toward the other and a yielding pressure device normally tending to separate the disks.

36. The combination of a sprocket wheel, a sprocket chain, two disks arranged on opposite sides of the sprocket wheel to rotate in unison with it, the adjacent faces of said disks beveled from their centers outwardly and away from each other, centrifugally actuated means for moving one toward the other and a yielding pressure device normally tending to separate the disks.

37. The combination of a sprocket wheel, a sprocket chain, two disks on opposite sides of the sprocket wheel to rotate with it and having their adjacent faces beveled from their centers outwardly and away from each other, and means for jointly moving the disks toward the sprocket wheel.

38. The combination of a sprocket wheel, a sprocket chain, two disks on opposite sides of the sprocket wheel to rotate with it and having their adjacent faces beveled from their centers outwardly and away from each other and automatic means for jointly moving the disks toward the sprocket wheel.

39. The combination of a sprocket wheel, a sprocket chain, two disks on opposite sides of the sprocket wheel to rotate with it and having their adjacent faces beveled from their centers outwardly and away from each other and centrifugally actuated means for jointly moving the disks toward the sprocket wheel.

40. The combination of a sprocket wheel, a sprocket chain, two disks on opposite sides of the sprocket wheel to rotate with it and having their adjacent faces beveled from

their centers outwardly and away from each other, means for jointly moving the disks toward the sprocket wheel and yielding pressure devices normally tending to jointly move said disks away from the sprocket wheel.

41. The combination of a sprocket wheel, a sprocket chain, two disks on opposite sides of the sprocket wheel to rotate with it and 10 having their adjacent faces beveled from their centers outwardly and away from each other, automatic means for jointly moving the disks toward the sprocket wheel and yielding pressure devices normally tending 15 to jointly move said disks away from the sprocket wheel.

42. The combination of a sprocket wheel, a sprocket chain, two disks on opposite sides of the sprocket wheel to rotate with it and 20 having their adjacent faces beveled from their centers outwardly and away from each other, centrifugally actuated means for jointly moving the disks toward the sprocket wheel and yielding pressure devices normally tending 25 to jointly move said disks away from the sprocket wheel.

43. The combination of a sprocket wheel, a sprocket chain, two disks on opposite sides of the sprocket wheel to rotate with it and 30 having their adjacent faces beveled from their centers outwardly and away from each other, means for jointly moving the disks toward the sprocket wheel and means for limiting the movement of the sprocket chain 35 outwardly between the disks.

44. The combination of a sprocket wheel, a sprocket chain, two disks on opposite sides of the sprocket wheel to rotate with it and having their adjacent faces beveled from 40 their centers outwardly and away from each other, means for jointly moving the disks toward the sprocket wheel and adjustable means for limiting the movement of the sprocket chain outwardly between the disks.

45. The combination of a sprocket wheel, a sprocket chain, two disks on opposite sides of the sprocket wheel to rotate with it and having their adjacent faces beveled from 50 their centers outwardly and away from each other, means for jointly moving the disks toward the sprocket wheel and manually operated means for forcing the chain between the disks and into engagement with the sprocket wheel.

46. The combination of two rotatable disks with their adjacent faces inclined from 60 their axes outwardly and away from each other, a power transmitting chain between the disks and in engagement therewith and an independent automatic governor for each disk to move the disks jointly toward and away from each other.

47. The combination of two rotatable disks with their adjacent faces inclined from 65 their axes outwardly and away from each

other, a power transmitting chain between the disks and in engagement therewith and an independent centrifugal governor for each disk to move the disks jointly toward and away from each other.

48. The combination of two disks arranged to rotate in unison with their adjacent faces inclined from their axes outwardly and away from each other, a sprocket wheel centered between the disks 70 and arranged to rotate with them, a sprocket chain extended between the disks and designed to engage the sprocket wheel and means for jointly moving the disks toward and from each other to move the sprocket 75 chain to and from engagement with the sprocket wheel and to maintain it centered over the sprocket wheel when out of engagement with the sprocket wheel.

49. A sprocket wheel, two disks on opposite sides of the sprocket wheel capable of movement to and from the sprocket wheel and arranged to rotate in unison with it having their adjacent faces inclined from their axes outwardly and away from each 80 other, a sprocket chain between the disks and capable of engaging a sprocket wheel and an independent automatic governor for each disk capable of moving the disks toward and from each other in unison.

50. A sprocket wheel, two disks on opposite sides of the sprocket wheel capable of movement to and from the sprocket wheel and arranged to rotate in unison with it having their adjacent faces inclined from 90 their axes outwardly and away from each other, a sprocket chain between the disks and capable of engaging a sprocket wheel and an independent centrifugal governor for each disk capable of moving the disks 95 toward and from each other in unison.

51. The combination of a rotatable shaft, a sprocket wheel thereon, a disk adjacent to one side of the sprocket wheel capable of movement toward and from the sprocket 100 wheel and having its face adjacent to the sprocket wheel inclined from its axis outwardly and away from the sprocket wheel, a second disk on the other side of the sprocket wheel, a sprocket chain between the disks and capable of engaging the sprocket wheel and a centrifugal governing device connected with the first mentioned disk and designed to move the disk 105 toward the sprocket wheel by centrifugal action.

52. The combination of a rotatable shaft, a sprocket wheel thereon, a disk adjacent to one side of the sprocket wheel capable of movement toward and from the sprocket 110 wheel and having its face adjacent to the sprocket wheel inclined from its axis outwardly and away from the sprocket wheel, a second disk on the other side of the sprocket wheel, a sprocket chain between the disks 115 and capable of engaging the sprocket wheel and a centrifugal governing device connected with the first mentioned disk and designed to move the disk toward the sprocket wheel by centrifugal action.

and capable of engaging the sprocket wheel, a centrifugal governing device connected with the first mentioned disk and designed to move the disk toward the sprocket wheel 5 by centrifugal action and a spring acting in opposition to the governor.

53. The combination of a rotatable shaft, a sprocket wheel fixed thereto, a disk slidably mounted on the shaft and having an 10 inclined face adjacent to the sprocket wheel, a frame fixed to the shaft adjacent to the disk, a centrifugal governing device carried by the frame and acting upon the disk to move it toward the sprocket wheel, a 15 spring acting in opposition to the governing device, a disk mounted on the shaft on the opposite side of said sprocket wheel and a sprocket chain passed between the disks and capable of engaging the sprocket wheel.

54. The combination of a shaft, a disk 20 slidably mounted on the shaft, a frame fixed to the shaft adjacent to the disk, a weighted lever pivoted between the shaft and disk and formed with a tapered extension designed when the weighted lever is thrown outwardly by centrifugal force to wedge apart the disk and frame, a spring 25 tending to hold the disk and frame toward each other and anti-friction rollers on the disk and frame to engage the tapered extension.

55. The combination of a shaft, a frame 30 fixed to the shaft, a number of rollers on one face thereof, a disk slidably mounted on the shaft, pins extending through the disk and frame to cause them to rotate in unison and permitting them to move slidably toward and from each other, rollers on the face of the disk adjacent to those on the 35 frame, weighted levers fulcrumed to said pins and slidably mounted thereon, and having wedge-shaped extensions thereon to enter between the pairs of rollers and springs tending to hold the disk and frame 40 toward each other.

56. The combination of a driving means, a rotatable driven means, a flexible power transmitter passed around them, one of said 45 means comprising two adjacent sides positioned to admit the flexible power transmitter between them, one of said sides adjustable relative to the other, centrifugally actuated means for moving one of said sides relative to the other, and adjustable spring 55 actuated means acting in opposition to the centrifugally actuated means.

57. The combination of a driving means, a rotatable driven means, a flexible power transmitter passed around them, one of said 60 means comprising two adjacent sides positioned to admit the flexible power transmitter between them, one of said sides adjustable relative to the other, said sides normally separated far enough to avoid driving 65 engagement with the flexible power trans-

mitter and a centrifugally actuated governing device for moving the movable side into driving engagement with the flexible power transmitter.

58. The combination of a driving means, 70 a rotatable driven means, a flexible power transmitter passed around them, one of said means comprising two adjacent sides positioned to admit the flexible power transmitter between them, one of said sides adjustable relative to the other, said sides normally separated far enough to avoid driving engagement with the flexible power transmitter and a centrifugally actuated governing device for moving the movable side into 75 driving engagement with the flexible power transmitter, and a yielding pressure device tending to move the movable side out of driving engagement with the flexible power transmitter.

59. The combination of a driving means, a rotatable driven means, a flexible power transmitter passed around them, one of said means comprising two adjacent sides positioned to admit the flexible power transmitter between them, the adjacent faces of said sides tapered from a maximum distance from each other near their peripheries, to a minimum distance from each other near their centers, one of said sides adjustable 95 relative to the other, said sides normally separated far enough to avoid driving engagement with the flexible power transmitter and a centrifugally actuated governing device for moving the movable side into 100 driving engagement with the flexible power transmitter.

60. The combination of a driving means, a rotatable driven means, a flexible power transmitter passed around them, one of said 105 means comprising two adjacent sides positioned to admit the flexible power transmitter between them, the adjacent faces of said sides tapered from a maximum distance from each other near their peripheries to a minimum distance from each other near their centers, one of said sides adjustable 110 relative to the other, said sides normally separated far enough to avoid driving engagement with the flexible power transmitter, a centrifugally actuated governing device for moving the movable side into driving engagement with the flexible power transmitter and a yielding pressure device extending to move the movable side out of 120 driving engagement with the flexible power transmitter.

61. The combination of a driving means, a rotatable driven means, a flexible power transmitter passed around them, one of said 125 means comprising two adjacent sides positioned to admit the flexible power transmitter between them, one of said sides adjustable relative to the other, centrifugally actuated means for moving one of said sides 130

relative to the other, adjustable spring actuated means acting in opposition to the centrifugally actuated means, and means for forcing the flexible power transmitter 5 toward the center of said sides.

62. The combination of a driving means, a rotatable driven means, a flexible power transmitter passed around them, one of said means comprising two adjacent sides positioned to admit the flexible power transmitter between them, one of said sides adjustable relative to the other, said sides normally separated far enough to avoid driving engagement with the flexible power transmitter, a centrifugally actuated governing device for moving the movable side into driving engagement with the flexible power transmitter, and means for forcing the flexible power transmitter toward the center of said sides.

63. The combination of a driving means, a rotatable driven means, a flexible power transmitter passed around them, one of said means comprising two adjacent sides positioned to admit the flexible power transmitter between them, one of said sides adjustable relative to the other, said sides normally separated far enough to avoid driving engagement with the flexible power transmitter, a centrifugally actuated governing device for moving the movable side into driving engagement with the flexible power transmitter, a yielding pressure device tending to move the movable transmitter and 30 means for forcing the flexible power transmitter toward the center of said sides.

64. The combination of a driving means, a rotatable driven means, a flexible power transmitter passed around them, one of said means comprising two adjacent sides positioned to admit the flexible power transmitter between them, the adjacent faces of said sides tapered from a maximum distance from each other near their peripheries, to a 45 minimum distance from each other near their centers, one of said sides adjustable relative to the other, centrifugally actuated means for moving one of said sides relative to the other, adjustable spring actuated 50 means acting in opposition to the centrifugally actuated means, and means for forcing the flexible power transmitter toward the center of said sides.

65. The combination of a driving means, 55 a rotatable driven means, a flexible power transmitter passed around them, one of said means comprising two adjacent sides positioned to admit the flexible power transmitter between them, the adjacent faces of

said sides tapered from a maximum distance 60 from each other near their peripheries, to a minimum distance from each other near their centers, one of said sides adjustable relative to the other, said sides normally separated far enough to avoid driving engagement with the flexible power transmitter, a centrifugally actuated governing device for moving the movable side into driving engagement with the flexible power transmitter and means for forcing the 70 flexible power transmitter toward the center.

66. The combination of a driving means, a rotatable driven means, a flexible power transmitter passed around them, one of said means comprising two adjacent sides positioned to admit the flexible power transmitter between them, the adjacent faces of said sides tapered from a maximum distance 75 from each other near their peripheries, to a minimum distance from each other near their centers, one of said sides adjustable relative to the other, said sides normally separated far enough to avoid driving engagement with the flexible power transmitter, a centrifugally actuated governing device for 80 moving the movable side into driving engagement with the flexible power transmitter, a yielding pressure device tending to move the movable side out of driving engagement with the flexible power transmitter, a yielding pressure device tending to move the movable side out of driving engagement with the flexible power transmitter, and means for forcing the flexible power transmitter toward the center of said sides.

67. In a driving mechanism, the combination with a shaft having a sprocket wheel 95 thereon, of a pair of friction disks supported on said shaft adjacent the sprocket wheel and movable relatively to and from each other, and a sprocket chain adapted to co-operate with the friction disks or with the 100 sprocket wheel.

68. In a driving mechanism, the combination with a shaft having a sprocket wheel thereon, of a pair of friction disks supported on said shaft adjacent the sprocket wheel 105 and movable relatively to and from each other, a sprocket chain adapted to co-operate either with the friction disks or with the sprocket wheel, and yielding means tending to bring said disks together during operation, said disks having diverging surfaces adjacent the sprocket wheel to carry the 110 chain out of engagement therewith.

Des Moines, Iowa, December 6, 1905.
